UNITED STATES PATENT OFFICE.

JOHN M. HAMOR, OF PHILADELPHIA, PENNSYLVANIA, ASSIGNOR TO
JOHN M. ROGERS, OF WILMINGTON, DELAWARE.

ROCK-DRILL.

SPECIFICATION forming part of Letters Patent No. 787,376, dated April 18, 1905.

Application filed September 27, 1904. Serial No. 226,113.

To all whom it may concern:

Be it known that I, JOHN MORRIS HAMOR, a citizen of the United States, residing at Philadelphia, county of Philadelphia, and State of Pennsylvania, have invented a new and useful Improvement in Rock-Drills, of which the following is a full, clear, and exact description, reference being had to the accompanying drawings, which form a part of this specification.

My invention relates to rock-drills, and particularly to the controlling-valve mechanism therefor.

The object of the invention is to so construct the valve as to enable it to be assembled, removed, or reassembled without the necessity of nice adjustments of the parts or the possession of any particular skill by the workmen.

The invention also has for its object to provide a valve that will not get out of order in use.

The invention also has for its object to provide a valve that will be simple in construction and cheap to construct.

The invention consists of the general and specific construction and arrangement of parts hereinafter set out, and particularly pointed out in the claims.

While the invention is particularly designed for embodiment in rock-drills, it may be found applicable to other impact-tools operated by steam or compressed air.

In the drawings, Figure 1 is a longitudinal section through the drill. Fig. 2 is a section on the line 2 2, Fig. 1. Fig. 3 is a section on the line 3 3 of Fig. 1. Fig. 4 is a section on the line 4 4 of Fig. 1. Fig. 5 is an end view of the valve. Fig. 6 is a side view of the valve looking toward the right of Fig. 5. Fig. 7 is a side view of the valve looking toward the left of Fig. 5.

a is the supporting-frame; *b*, the drill-head; *c*, the piston, and *d* the cylinder.

e is the nut working on the threaded shaft *f*, operated by the crank *g*, whereby the cylinder and piston may be carried along the frame.

h is the ratchet on shaft *i*, which is en-

gaged by pawls (not shown) on the rotatable 50 ring *j*, which ring is provided with pressure surfaces actuated by ports alternately connected with pressure and exhaust in the operation of the piston, whereby the piston is given the usual step-by-step rotation, these parts 55 not being herein shown, as the same form no part of my invention and are fully set forth in Letters Patent issued to me November 9, 1897, No. 593,214.

Referring now to the parts embodying my 60 invention, *k* is the valve-easing, having the covers *l m* at each end of and forming part of the valve-easing.

n is a rotary valve within the valve-easing. *o p* are nozzles (see Fig. 2) projecting from 65 the covers *l m*, respectively, one of said nozzles being closed by a plug *s*, while the other is connected with the pipe *q*, leading from a source of pressure-supply.

10 11 are passages formed in and extending lengthwise of the covers *l m*, respectively, and communicating with nozzles *o p*, respectively. 12 13 are channels formed in the valve-easing and extending one alongside of the valve and the other along the other side 75 of the valve, each channel communicating with one end of each of the passages 10 11. These passages or channels 10 11 12 13 are therefore in constant communication with the source of pressure-supply. 80

14 15 are channels formed in the periphery of the valve and extending longitudinally thereof adjacent to the channels 12 13, respectively.

16 is a chamber formed in the periphery of 85 the valve and extending longitudinally thereof, and 17 18 constricted ports connecting the chamber 16 with the channels 14 15, respectively.

r is a valve-piston secured to the valve-easing and extending into the chamber 16, said piston acting as a wall to divide chamber 16 longitudinally and also performing the function of limiting the rotary movement of the valve in each direction. The ports 17 18 lead 95 to the chamber 16 on opposite sides of the valve-piston *r*.

It will be seen from Fig. 1 that whether the

valve is moved to the right or to the left the channels 14 and 15 are in constant communication with the channels 12 and 13, respectively. Therefore it will be understood that 5 channels 14 and 15 are constantly supplied with motive fluid and that there is a constant leakage of the same through ports 17 and 18 into chamber 16, so that there is a balanced pressure against the sides of the valve-piston 10 *r*, tending to hold the valve balanced and immovable. The reciprocation of the valve is effected by allowing the pressure to exhaust alternately from opposite sides of the valve-piston *r*, as will be hereinafter described. 15 19 is a channel formed in the periphery of the valve and extending longitudinally thereof midway between the supply-channels 14 and 15. 20 21 are passages formed partly in the cylinder and partly in the valve-casing, leading from opposite ends of the piston-chamber to the valve-chamber. 25

22 is a passage formed partly in the valve-casing and partly in the cylinder, leading from 30 the valve-chamber at a point between the ends of passages 20 and 21 to an exhaust-chamber 23 formed in the cylinder.

24 25 are openings (see Fig. 2) extending through the wall of the cylinder into exhaust-chamber 23, one of said openings being closed 35 by the plug *v*, while an exhaust-pipe *w* is secured in the other opening. It will be observed that the channel 19 is always in communication with the exhaust, whether the valve is in one or the other of its extreme positions.

It will be understood that when the valve is in the position shown in Fig. 1 the supply-channel 15 registers with the passage 21, while 40 the exhaust-channel 19 registers with the passage 20, thereby causing the piston to move from right to left, and that when the valve is in the opposite position the supply-channel 14 registers with the passage 20, while the 45 exhaust-channel 19 registers with the passage 21, thereby causing the piston to be returned to the position shown in Fig. 1.

I will now describe the means whereby the operation of the valve is controlled by the piston 50 ton.

24 is a passage formed partly in the valve-casing and partly in the cylinder, extending from one side of chamber 16 to the piston-chamber.

55 25 is a passage formed partly in the valve-casing and partly in the cylinder, extending from the other side of chamber 16 to the piston-chamber, one of these passages opening at one side and the other opening at the other 60 side of the longitudinal center of the piston-chamber. 26 is an annular channel formed in the piston.

27 28 are ports extending through the wall of the cylinder from exhaust-chamber 23 to 65 the piston-chamber, the openings into the pis-

ton-chamber being in circumferential alignment, respectively, with the openings into the piston-chamber of passages 24 and 25.

When the parts are in the position shown in Fig. 1, the piston will move from right to left, as before described. This causes the channel 26 to connect with passage 24 and closes the piston-chamber end of passage 25, permitting the motive fluid to exhaust from the right-hand side of piston *r*. By reason 75 of the constant pressure on the left-hand side of piston *r* the valve is turned to its other position, thereby, as before described, causing the piston to move from left to right. This causes the channel 26 to connect with passage 25 and closes the piston-chamber end of passage 24, permitting the motive fluid to exhaust from the left-hand side of piston *r*. By reason of the constant pressure on the right-hand side of piston *r* the valve is returned to the position shown in Fig. 1. This completes the cycle of operation of the valve and piston.

29 represents bolt-holes in the valve-casing, and 30 bolt-holes in the covers, through which 90 bolts *y* are passed to secure the covers to the casing.

z represents bolts by means of which the valve-casing is secured to the cylinder.

It will be observed that the two sides of the 95 valve and of the valve-casing, as well as the two ends and the two covers thereof, are exact counterparts, rendering it virtually impossible for a workman to improperly assemble the parts. The construction is such that no nice adjustments are required, the valve simply being placed within its casing in any position and the casing being placed in either of its two possible positions between the covers, the bolt-holes in casing and covers being necessarily brought into registry before inserting the bolts therethrough to insure a proper adjustment of the casing and covers. The valve mechanism is simple in construction, efficient in operation, and will not get 100 out of order in use.

Having now fully described my invention, what I claim, and desire to protect by Letters Patent, is—

1. The combination, with the cylinder, the piston-chamber and piston therein, and the rotary valve and its casing, of a passage in the valve-casing adapted to be placed in constant communication with the exhaust, channels in opposite sides of the valve-casing adapted to be placed in constant communication with the supply, three channels in the valve adapted in either position of the valve to communicate with the three channels in the valve-casing, respectively, and passages leading from the ends of the piston-chamber to the valve-chamber, the valve, in its two movements, causing the exhaust-channel in the valve to connect with one or the other of said passages and causing one or the other of the supply-chan-

nels in the valve to connect with its corresponding passage, substantially as described.

2. The combination, with the cylinder, the piston-chamber and piston therein, and the rotary valve and its casing, of a passage in the valve-casing adapted to be placed in constant communication with the exhaust, channels in opposite sides of the valve-casing, passages in opposite ends of the valve-casing connecting with said channels and adapted to be placed in constant communication with the supply, three channels in the valve adapted in either position of the valve to communicate with the three channels in the valve-casing respectively, and passages in the cylinder connecting the ends of the piston-chamber with the valve-chamber, the valve, in its two movements, causing the exhaust-channel in the valve to connect with one or the other of said cylinder-passages and causing one or the other of the supply-channels in the valve to connect with the corresponding cylinder-passage, substantially as described.

3. The combination, with the cylinder, the piston-chamber and piston therein, and the valve and its casing, of a stationary piston on the valve-casing extending into a valve-piston chamber in the valve, three channels in the valve, ports connecting the two outside channels respectively with opposite sides of the valve-piston chamber, the said two outside channels being adapted to be placed in constant communication with the supply and the middle channel being adapted to be placed in constant communication with the exhaust, means whereby the valve, in its movement, connects opposite ends of the main piston-chamber respectively with the exhaust-channel and one of said supply-channels, and means controlled by the main piston to place opposite sides of the valve-piston chamber alternately in communication with the exhaust, substantially as described.

4. The combination, with the cylinder, the piston-chamber and piston therein, and the valve and its casing, of a stationary piston on the valve-casing extending into a valve-piston chamber in the valve, three channels in the valve, ports connecting the two outside channels respectively with opposite sides of the valve-piston chamber, three channels in the valve-casing adapted to register respectively with the three channels in the valve in either position of the valve, the two outside valve-casing channels being adapted to be placed in constant communication with the supply and the middle valve-casing channel being adapted to be placed in constant communication with the exhaust, means whereby the valve, in its movement, connects opposite ends of the main piston-chamber respectively with the middle valve-channel and one of the outside valve-channels, and means controlled by the main piston to place opposite sides of the

valve-piston chamber alternately in communication with the exhaust, substantially as described. 65

5. The combination, with the cylinder, the piston-chamber and piston therein, and the valve and its casing, of a stationary piston on the valve-casing extending into a valve-piston chamber in the valve, three channels in the valve, ports connecting the two outside channels respectively with opposite sides of the valve-piston chamber, three channels in the valve-casing adapted to register respectively with the three channels in the valve in either position of the valve, two passages in the end of the valve-casing connected with the two outside valve-casing channels, said two passages being adapted to be placed in constant communication with the supply, an exhaust-chamber communicating with the middle valve-casing channel, means whereby the valve in its movement, connects opposite ends of the main piston-chamber respectively with the middle valve-channel and one of the outside valve-channels, and means controlled by the main piston to place opposite sides of the valve-piston chamber alternately in communication with the exhaust, substantially as described. 80 85

6. The combination, with the cylinder, the piston-chamber and piston therein and the valve and its casing, of a stationary piston on the valve-casing extending into a piston-chamber formed in the valve, means whereby motive fluid may be constantly admitted to said valve-piston chamber on both sides of said valve, passages extending from opposite sides of the valve to the piston-chamber, an annular channel formed in the piston adapted in the movement of the piston to be alternately connected with said passages, ports in said piston-chamber adapted to be placed in constant communication with the exhaust, said annular channel being adapted in the movement of the piston to be alternately connected with said ports, whereby, in the movement of the piston, the opposite sides of the valve-piston are alternately placed in communication with the exhaust, thereby shifting the valve, and means whereby the valve, so shifted, controls the reciprocation of the piston, substantially as described. 90 95 100 105 110 115

7. The combination, with the cylinder, the piston-chamber and the piston therein, of a cylindrical valve having formed in its face a piston-chamber and oppositely thereto an exhaust-channel and on each side of the exhaust-channel, a supply-channel, a valve-casing having formed on its opposite inner faces supply-channels extending longitudinally of the valve and in constant communication with the supply-channels in the valve-face in either position of the valve, said valve-casing having formed in its ends passages each of which connects the corresponding ends of the sup- 120 125

- 4
- ply-channels in the valve-casing, one at least of said passages being adapted to be connected with the supply, means whereby the valve-channels, in the movement of the valve, controls the reciprocation of the piston, and means whereby the piston, in its reciprocation, creates an unbalancing of pressure in the piston - valve chamber, substantially as described.
10. 8. The combination, with the cylinder, the piston-chamber, and the piston therein, of a cylindrical valve having supply and exhaust passages and a valve-piston chamber, a valve-casing having supply and exhaust passages communicating with the valve-piston chamber and the supply and exhaust passages in the valve, passages leading to the ends of the piston-chamber for controlling the admission of motive fluid thereto and passages controlled by the piston for actuating the valve, the arrangement of said passages in the valve and valve-casing being such that the valve-casing and valve may each be divided longitudinally or transversely into two halves substantially exact counterparts of each other, substantially as described.
9. The combination, with the cylinder and piston therein, of a rotary valve alongside the cylinder and whose axis extends at right angles thereto, a valve-casing secured to the cylinder and inclosing the valve, a cover at each end of the valve, there being alining bolt-holes in casing and covers through which bolts extend to secure the same together, motive-fluid passages in the cylinder and valve, and motive-fluid passages in the valve-casing and covers, the ends of the passages in each cover communicating with the corresponding ends of passages in the valve-casing, thereby forming an air space or passage in the valve-casing and covers entirely surrounding the valve, whereby the valve and piston, in their reciprocation, each control the reciprocation of the other, substantially as described.
45. 10. The combination, with the cylinder and piston therein, of a rotary valve, a valve-casing secured to the cylinder and inclosing the valve, a cover at each end of the valve secured to the casing, motive-fluid passages in the cylinder and valve, and motive-fluid passages in the valve-casing and covers, the ends of the passages in each cover communicating with the corresponding ends of passages in the valve-casing, thereby forming an air space or passage in the valve-casing and covers entirely surrounding the valve, whereby the valve and piston, in their reciprocations, each control the reciprocation of the other, the arrangement of passages being such that the valve-casing and valve may each be divided longitudinally or transversely into two substantially exact counterpart halves, the two
- covers being also substantially exact counterparts, substantially as described.
11. The combination, with the cylinder, the piston-chamber and piston therein, the rotary valve, and the valve-casing and end covers therefor, of passages connecting opposite ends of the main piston-chamber with the valve-chamber, an exhaust-chamber in the cylinder, oppositely-disposed openings therefrom adapted to receive an exhaust-pipe, a passage connecting the exhaust - chamber with the valve - chamber, an exhaust - channel formed in and extending longitudinally of the valve and in constant communication with the last-named passage, two supply-channels formed in the valve and extending longitudinally of the valve on either side of the exhaust-channel, supply-channels in the valve-casing extending longitudinally of the valve and in constant communication respectively with the supply-channels in the valve, a cover at each end of the valve - casing, supply - passages in each cover the opposite ends of each of which communicate respectively with the said supply-channels in the valve-casing, an opening from each supply-passage adapted to receive a supply-pipe, a valve-piston chamber formed in the periphery of and extending longitudinally of the valve, a valve-piston on the valve-casing projecting within said valve-piston chamber, ports connecting said valve-piston chamber with the supply-channels formed in the valve, a passage connecting one side of said valve-piston chamber with the main piston-chamber, on one side of its longitudinal center, a passage connecting the other side of said valve-piston chamber with the main piston-chamber on the other side of its longitudinal center, ports connecting the exhaust-chamber with the main piston-chamber, the openings thereof into the main piston-chamber being in substantial circumferential alignment respectively with the openings into the main piston-chamber of the last-named passages, and an annular channel formed in the main piston, the valve being adapted to rotate on its axis and thereby alternately connect the passages leading to the ends of the main piston-chamber with the exhaust, and the piston, by its reciprocation, alternately connecting the opposite sides of the valve-piston chamber with the exhaust by means of said annular channel and the said alining ports and passages, substantially as described.
- In testimony of which invention I have hereunto set my hand, at Philadelphia, Pennsylvania, on this 23d day of September, 1904.
